UNITED STATES PATENT OFFICE.

JOSEPH FRANÇOIS EYRAUD, OF LYON, FRANCE, ASSIGNOR, BY MESNE ASSIGNMENTS, TO THE BRYANT ELECTRIC COMPANY, OF BRIDGEPORT, CONNECTICUT, A CORPORATION OF CONNECTICUT.

ELECTRIC SWITCH.

Application filed February 14, 1921, Serial No. 444,804. Renewed April 7, 1925.

To all whom it may concern:

Be it known that I, JOSEPH FRANÇOIS EYRAUD, a citizen of the French Republic, of Lyon, France, have invented certain new and useful Improvements in Electric Switches, of which the following is a specification.

My invention relates to electric switches and particularly to rotary snap switches. My improved switch mechanism is constructed to obtain a snap make and break action on rotation of the switch spindle in either direction. To this end the switch mechanism comprises an escapement having a series of fixed stops spaced around the switch spindle, said stops affording between them interspaces or recesses to receive a detent or latch bolt. The latter is appropriately connected to the rotary switch blade or pole member for rotation therewith. A cam on the rotary switch spindle serves to free the detent from the fixed stops after the switch operating spring has been stressed.

In the accompanying drawings—

Fig. 1 is a section on the line A—A, Fig. 2;

Fig. 2 is a section on the line B—B, Fig. 1;

Figs. 3, 4 and 5 are more or less diagrammatic sectional views illustrating the operation of the escapement mechanism; and

Figs. 6, 7 and 8 are similar views illustrating the operation of the switch spring.

The switch as shown comprises an insulating base *b* on which is secured a member *a* shaped to afford a series of projections or teeth *c* constituting fixed stops with recesses between them. Engaged between the opposed faces of adjacent stops *c* is a detent bolt or latch *d* mounted on an eccentric *e* fixed to the rotary switch spindle *g*. The axis of rotation *f* of the spindle *g* is aligned with the longitudinal center line of the detent *d* which is thus symmetrical with respect to the axis of the spindle.

A pole member or switch blade *j* is engaged between and suitably insulated from washers *i* and *k* on the sleeve *l* journaled freely on the rotary spindle *g*. A pin and slot engagement between the washer *i* and the detent *d* insures the rotation of the pole piece with the detent, while at the same time permitting the in and out play of the detent with respect to the stops *c* on actua-

tion of the switch. At its lower end the spindle *g* is freely journaled in the bushing *m* beneath which the end of the spindle may be headed over or otherwise secured.

The switch operating coil spring *p* arranged on the spindle *g* engages between its offset ends the lugs *k'* and *r'*. The lug *k'* is fast with the pole carrier washer *k*, while the lug *r'* is fast with the washer *r* fixed to the shaft *g*. The two lugs are spaced different radial distances from the spindle so that they may pass each other on rotation of the spindle in either direction by means of the button *n* thereon.

The operation of the switch is as follows. If the button *n* be turned clockwise (arrow Fig. 3) the lug *r'* moves out of radial alignment with the lug *k'*, since the pole carrier is temporarily held by the detent *d* against rotation and the spring *p* thus placed under stress. As the spindle rotates, its eccentric *e* causes the detent *d* to assume first a non-radial position with respect to the spindle, and second (on rotation of the cam more than 90°) to be withdrawn past the detaining face of the stop *c* which opposes rotation in the same direction as the spindle. As the detent *d* escapes the nose of the stop *c*, the spring *p* bearing against the lug *k'* causes the pole piece *j* and detent *d* to rotate clockwise together by reason of the pin and slot connection therebetween. During this rotation the detent *d*, journaled on cam *e* (now relatively stationary) is forced outward and its meeting side or margin impinges against the opposed face of the next succeeding stop *c* (Fig. 4). The switch bar or pole piece is thus halted in its next succeeding position.

Upon release of the spindle *g*, which has been rotated slightly more than 90° to effect the escapement operation, the leg of spring *p* which bears against lug *r'*, forces the latter into radial alignment with the lug *k'*. This slight reverse rotation of the spindle and cam causes the detent to re-assume its radial position (Fig. 2) in its new station.

Rotation of the spindle in opposite or contra-clockwise direction operates the escapement in opposite direction, but in precisely the same fashion, owing to the fact that the escapement mechanism is symmetrical.

The opposed faces of adjacent stops may diverge inwardly (Figs. 2 to 4), in which

case the sides of the detent may be parallel; or alternatively (Fig. 5) the opposed faces of the adjacent stops may be parallel and the side faces of the detent converge inwardly, after the fashion of a fish tail. In both instances the end of the detent is snugly engaged between the opposed faces of adjacent stops when the mechanism is in a normal position of rest, while the angular withdrawal or rocking out of the detent by the cam is nevertheless possible.

With the understanding that my invention may be embodied in various modified constructions which have substantially the same action, I claim as my invention—

1. In a device of the character described the combination of a base a hollow substantially cruciform member mounted on said base, a shaft perpendicular to the plane of said cruciform member and arranged centrally thereof, an eccentric keyed on said shaft within said cruciform member a collar mounted on said eccentric a symmetrically shaped lateral extension on said collar having approximately the width of the arms of the cruciform member and adapted to engage therein, a pin on the symmetrical axis of said extension, a washer carried by said shaft and having a radial groove in which said pin engages, a second washer on said shaft contact arms mounted on said shaft between said washers, fixed contact members co-acting with said contact arms, a button for rotating said shaft, means for supporting said shaft a helical spring surrounding said shaft between said second washer and the base of said button and having its ends bent away from said shaft a pin on said second washer adapted to engage with one of said ends and a pin mounted in said button adapted to engage with the other of said ends.

2. A rotary snap switch having a reversibly rotatable switch blade, a reversibly rotatable spindle, a driving spring operatively interposed between the same, and an escapement mechanism for temporarily detaining the switch blade during the rotation of the spindle in either direction, said mechanism including a series of fixed stops spaced around the spindle, a rotatable latch for detaining the switch blade and normally engaged between adjacent stops in substantially radial position with respect to the spindle, and means operated by the spindle upon its rotation in either direction for withdrawing the latch in non-radial position from the stops, the engaging faces of the latch and stops being shaped to afford an inwardly divergent angular clearance therebetween which permits the latch to freely assume a non-radial position with respect to the spindle during the withdrawal operation.

3. A rotary snap switch having a reversibly rotatable switch blade, a reversibly rota-

table spindle, a driving spring operatively interposed between the same, and an escapement mechanism for temporarily detaining the switch blade during the rotation of the spindle in either direction, said mechanism including a series of fixed stops spaced around the spindle, a rotatable latch for detaining the switch blade and normally engaged without substantial lost motion between the parts, and means operated by the spindle, upon its rotation in either direction, for withdrawing the latch in angular position from engagement with the stops, the width of the latch corresponding substantially to the distance between the stops at the point of engagement therebetween when the parts are at rest, while the engaging faces of the latch and stops are shaped to afford a clearance therebetween which permits the latch to freely assume an angular position during its withdrawal.

4. A rotary snap switch having a reversibly rotatable switch blade, a reversibly rotatable spindle, a driving spring operatively interposed between the same, and an escapement mechanism for temporarily detaining the switch blade during the rotation of the spindle in either direction, said mechanism including a series of fixed stops spaced around the spindle, a rotatable latch for detaining the switch blade and normally engaged without substantial lost motion between the parts, and means operated by the spindle, upon its rotation in either direction, for withdrawing the latch in angular position from engagement with the stops, the width of the latch corresponding substantially to the distance between the stops at the point of engagement therebetween when the parts are at rest, while the engaging faces of the latch and stops are shaped to afford a clearance therebetween which permits the latch to freely assume an angular position during its withdrawal.

5. In a rotary snap switch, a stop plate having a series of stop lugs, each provided with a pair of latch-engaging faces which lie at an angle to each other, the opposed faces of adjacent stops lying parallel to each other, in combination with a latch adapted to be engaged and detained between adjacent stops, said latch comprising a fish tail plate, the opposite side margins of the fish tail forming impact faces.

6. A rotary snap switch comprising a stop plate having a series of stop lugs, the opposed faces of adjacent stops being substantially parallel, in combination with a latch adapted to enter and be engaged between the opposed faces of adjacent stops, the engaging faces of said latch being angled toward each other.

7. In an electric switch, a stop plate hav-

ing stop lugs, the opposed faces of adjacent stops being substantially parallel to each other, in combination with a cam-operated latch having an end dimension substantially 5 corresponding to the distance between the opposed faces of adjacent stops, and a less dimension toward the cam to afford clearance between the sides of the latch and the stops when the latch is rocked by the rotation of the cam.

8. In an electric switch, a stop plate having stationary stop lugs, a reversibly rotatable switch spindle, a cam fast with said spindle, and a latch operably associated with 15 said cam and shaped for end engagement between adjacent stop lugs in normal position of said cam, for angular withdrawal therefrom on rotation of the cam in either direction, and for lateral flat face impact with 20 the side of a stop lug at the end of its throw.

9. In an electric switch, a stop plate having stop lugs, a reversibly rotatable switch spindle, a cam fast with said spindle, a detent plate, a latch having an offset lug engaging said detent plate for rotation therewith, said latch being operatively associated with said cam, and being shaped for engagement with the stop lugs of the stop plate 30 and movable out of engagement therewith on rotation of the cam in either direction.

10. In an electric switch, a reversibly rotatable switch spindle, stops spaced around the spindle and having flat impact faces on 35 their opposite sides, a latch plate having flat impact faces normally engaged between the impact faces of adjacent stops and extending outward a shorter distance than the latter, and means operated by the spindle on 40 its rotation in either direction for shifting the latch out of engagement with said stops, the adjacent faces of the latch and stops being shaped to afford an inwardly diverging clearance therebetween when the parts are 45 at rest.

11. In an electric switch, a reversibly rotatable switch spindle, a series of fixed stops spaced around the spindle, a latch normally engaged between adjacent stops, the sides of 50 said latch and of the stops being shaped to afford pairs of flat faces which meet substantially in a plane in impact position, but afford an inwardly-directed angular clearance therebetween when the parts are 55 at rest, a spring operatively interposed between the spindle and latch for rotating the latter in either direction, and means operative upon the rotation of the spindle in either direction for withdrawing the latch 60 from engagement between the stops.

12. In a rotary snap switch, a reversibly rotatable switch spindle, a series of stops spaced around the spindle, each of said stops having mutually approaching surfaces which meet to afford a quick escape-

ment juncture, together with a latch operatively associated with the rotary spindle and normally engaged between the opposed surfaces of adjacent stops, said latch being adapted for withdrawal past the escapement juncture of the surfaces of one or other of the stops between which it is engaged, depending upon the direction of rotation of the spindle.

13. In a rotary snap switch, a reversibly 75 rotatable switch spindle, a series of stops spaced around the spindle, each of said stops having a pair of flat stop faces meeting toward the spindle in a sharp escapement edge, together with a latch operatively 80 associated with the rotary spindle and normally engaged between the opposed faces of adjacent stops, said latch being adapted for withdrawal past the escapement edge of one or the other of said stops between 85 which it is engaged, depending upon the direction of rotation of the spindle.

14. In a rotary snap switch, a stop plate centrally pierced to accommodate a reversibly rotatable switch spindle, and stop lugs 90 formed in said plate and spaced around said central piercing, each of said lugs comprising a pair of flat stop faces inclined toward each other and meeting on a sharp escapement edge faced toward the center 95 of the plate.

15. In a snap switch, the combination of a movable pole member, an actuating shaft, a spring operatively connecting said shaft and said pole member, spaced stationary 100 stops fixedly supported about said shaft, a detent connected to rotate with said pole member and having one end normally disposed between two of said stops, and an operative cam connection between said shaft 105 and said detent positively retracting and advancing the detent with respect to the stationary stops.

16. In a snap switch, the combination of a movable pole member, an actuating shaft, 110 a spring connecting said shaft and said pole member and operating to move said pole member in either direction with a snap action, fixed stationary stops spaced about said shaft, a detent connected with the pole member to rotate therewith and having its operative end of a width corresponding to the spacing of said stops, and an operative cam connection between said shaft and said detent positively retracting and advancing 115 the detent with respect to the stationary stops.

17. In a snap switch, the combination of a movable pole member, an actuating shaft, 125 a spring connecting said shaft and said pole member and operating to move said pole member in either direction with a snap action, fixed stationary stops spaced about said shaft, a detent connected to said pole member and having its operative end of a 130

width substantially equal to the spacing between said stops and normally to restrain movement of said pole member in both directions, and an operative cam connection between said shaft and said detent positively retracting and advancing the detent with respect to the stationary stops.

18. In a snap switch, the combination of a reversely rotatable pole member, a reversibly actuating shaft, a spring operatively connecting said shaft and said pole member to rotate the latter in either direction, fixed stops arranged about said shaft with relatively wide clearances between them, a detent connected to rotate with said pole member, one end of said detent having a

width only slightly less than the space between opposed faces of adjacent stops and normally located therebetween, and means connected to said shaft to move the detent out of engagement with the instant stop on rotation of the shaft in either direction, said detent during its rotation moving outward through the clearance between the instant stop and the succeeding stop in the direction of rotation, whereby full lateral impact between said detent and the succeeding stop is obtained. 20 25

In witness whereof I have signed this specification.

JOSEPH FRANCOIS EYRAUD.
